UNITED STATES PATENT OFFICE.

FERDINAND GABLER, OF TOPEKA, KANSAS.

CAR-BRAKE.

SPECIFICATION forming part of Letters Patent No. 554,593, dated February 11, 1896.

Application filed October 19, 1895. Serial No. 566,196. (No model.)

To all whom it may concern:

Be it known that I, FERDINAND GABLER, of Topeka, in the county of Shawnee and State of Kansas, have invented a new and useful 5 Improvement in Car-Brakes, of which the following is a specification.

The object of my invention is to provide a simple and effective car-brake.

It relates to that form of car-brake, here- 10 tofore patented by me January 24, 1893, No. 490,554, in which the brake-shoes are projected to contact against the wheels by the straightening of a pair of toggle-arms located between the two shoes operating against ad- 15 jacent wheels; and it consists in features of improvement which I will now proceed to describe with reference to the drawings, in which—

Figure 1 is an inverted plan view of a car- 20 truck provided with my improved brake. Fig. 2 is a sectional end view; Fig. 3, a sectional side view, and Fig. 4 is a detail of a modification.

In the drawings, A A are two brake-shoes 25 adapted to operate against the adjacent peripheries of the two wheels of a truck on the same side of the car. These shoes are suspended by hangers a a, and have a loose jointed connection with two horizontal toggle- 30 arms B B, which are jointed together at a middle point b, and at the same point are jointed by the same bolt or pintle-pin to a stem C extending transversely toward the middle of the car. The inner ends of these 35 two stems on opposite sides of the car are attached to a chain or flexible connection E. This chain passes around two pulleys F F fixed upon a stationary axis to the cross-timber of the car with a housing G², and also 40 around an intermediate pulley G, carried by a clevis H, which (see Fig. 3) is jointed to the lower end of the brake-lever J, fulcrumed upon a stationary support I and connected at its upper end to the brake chain and rod 45 K, through which the brakes are applied.

Whenever power is applied through the brake-chain to put on the brakes it deflects lever J, and, by pulling clevis H and pulley

G away from pulleys F F, it pulls out the chain E in the middle, draws inwardly the 50 stems C, and by straightening the toggle-arms B B thrusts the brake-shoes against the wheels, the power increasing as the toggles assume a position approximating a straight line.

When the strain on the brake-chain is released the brake-shoes are withdrawn from the wheels automatically by a spiral spring D, whose opposite ends are anchored to the 60 brake-shoes at a point directly between the same.

The above construction affords a simple, powerful, and easily-operated car-brake, in which the power is equally distributed to the 65 brake-shoes on opposite sides of the car, the pulleys F F and G and chain E forming an equalizing attachment that insures an even application of the power to the two sets of 70 brake-shoes, thus causing an even braking of the wheels on opposite sides of the car. 70

As a modification of the equalizing attachment, I may, as in Fig. 4, use two chains E' E' passing around pulleys F F and connected to the opposite ends of a lever or singletree G' fulcrumed in the middle to the clevis H 75 to accomplish the same result.

Having thus described my invention, what I claim as new, and desire to secure by Letters Patent, is—

A car-brake comprising two sets of brake- 80 shoes, two toggle-arms on each side of the car connected at their outer ends to the two adjacent brake-shoes and jointed to each other in the middle, a spiral spring arranged between the brake-shoes of each pair and 85 connected to the same, two transverse stems also connected to the middle joints of the toggles, and an equalizing device connected to the inner ends of the transverse stems and also to the brake-applying mechanism sub- 90 substantially as and for the purpose described.

FERDINAND GABLER.
